UNITED STATES PATENT OFFICE.

LOUIS GOLDSTEIN, OF NEW YORK, N. Y., ASSIGNOR TO GEO. BORGFELDT & CO., OF NEW YORK, N. Y., A CORPORATION OF NEW JERSEY.

DESIGN FOR A NUT-BOWL.

49,727.

Specification for Design.

Patented Oct. 3, 1916.

Application filed August 15, 1916. Serial No. 115,092. Term of patent 7 years.

To all whom it may concern:

Be it known that I, LOUIS GOLDSTEIN, a citizen of the United States, and resident of the borough of Brooklyn, county of Kings, city and State of New York, have invented a new, original, and ornamental Design for Nut-Bowls, of which the following is a specification.

Reference is to be had to the accompanying drawings in which—

Figure 1 is a perspective view of a nut bowl showing my new design and Fig. 2 is an elevation thereof.

I claim:

The ornamental design for a nut bowl as shown.

LOUIS GOLDSTEIN.
